ROLLER BLANK AND PROCESS OF MAKING
ROLLERS THEREFROMWilfred A. Beauchamp, Chicago, Ill., assignor to
The Youngstown Steel Door Company, Cleve-
land, Ohio, a corporation of Ohio

Application October 14, 1937, Serial No. 168,978

10 Claims. (Cl. 29—148.4)

This invention relates to roller blanks and the method of making rollers from said blanks.

It is an object of this invention to provide novel blanks from which eccentric rollers may be quickly and economically fashioned.

A further object is to provide a method whereby eccentric rollers embodying inner cores or disks and outer rims may be produced inexpensively and with a minimum of operations.

10 Other objects of the invention will become clear as the description thereof proceeds.

In the drawing forming part of this specification:

15 Figure 1 is a vertical section through a blank.
Figure 2 is a vertical section of roller rim ob-
tained from the blank and ready for assembly
into a roller.

20 Figure 3 is a vertical section of a roller core
obtained from the blank and prepared for assem-
bly into a roller.

25 Figure 4 is an elevation of an eccentric roller.
Figure 5 is a vertical section taken on line
5—5 of Figure 4.

30 Referring to the drawing, Figure 1 thereof
illustrates in section a novel forged blank from
which the main portions of the eccentric roller
illustrated in Figure 4 of the drawing are obtained.
This blank designated in its entirety by the ref-
erence numeral 10 is preferably forged although
35 it will be understood that the blank is not neces-
sarily limited to a forging. The blank 10 is pre-
pared so as to present in a unitary structure de-
fined core and rim portions 11 and 12. The cir-
cumference of the core 11 is indicated at 13 and
35 the inner circumference of the rim 12 is shown
at 14. Extending between these two circum-
ferences and connecting the core and rim into a
unitary structure is a connecting web 15 which
as clearly appears in Figure 1 of the drawing is
40 relatively thin. A similar web 16 may be formed
in the core 11 upon removal of which a prefer-
ably rectangular opening is provided in the core.
If desired, however, the core 16 may be omitted
45 from the blank and the rectangular opening here-
inafter referred to may be broached in the core
during the forging operation.

45 In Figure 2 of the drawing there is illustrated
the roller rim 12 after removal from the blank 10
and prepared for assembly into a completed
50 roller. Similarly in Figure 3 there is shown the
core 11 after removal from the blank 10 and pre-
pared for its assembly into a roller. In this
view the web 16 has been removed so that a
55 rectangular opening 17 referred to above is pro-
vided. Additionally the core 11 has been rab-
beted as indicated at 18 and 19 for a purpose
which will later appear.

In the removal of the rim and core from the
blank 10 the connecting web 15 may be cut away
in order to separate the core 11 from the rim 12.
The inner circumference of the rim is then
machined in order to remove the draft surfaces
produced by the forging operation. In like man-
ner the periphery of the core is machined to re-
move the draft surfaces and provide the rabbeted
10 portions 18 and 19. Also the web 16 in the core
is removed and the surfaces which it connects are
machined. While this series of steps may be
resorted to in properly removing the rim and
the core from the blank and preparing them for
15 assembly into a roller, it is preferred to chuck
the blank in a machine in such a way that the
core and rim portions of the blank will be prop-
erly supported so that the removal of the webs
15 and 16 and the machining of the inner circum-
ference of the rim and the outer portion of the
core may be performed in a single operation.

20 The prepared rim and core are assembled to-
gether with a roller bearing 20 to form the roller
21 illustrated in Figures 4 and 5 of the drawing.
25 It will be apparent from an examination of these
figures that the rectangular opening 17 is dis-
posed eccentrically with respect to the center
of the core thereby producing an eccentric roller.
Where it is desired to produce a roller that is
30 not eccentric the opening 17 may, of course, be
disposed concentric with the core. The roller
bearing 20 comprises in addition to a series of
rollers 22 a cage designated in its entirety by the
35 reference numeral 23, portions of which are dis-
posed in the rabbeted parts 18 and 19 of the
core as illustrated in Figure 5 of the drawing.

40 It will be apparent that numerous changes and
modification in the details of the invention will
be clear to those skilled in the art. It is intended,
therefore, that all such modifications and changes
be comprehended within this invention, which is
45 to be limited only by the scope of the claims
appended hereto.

I claim:

1. A cylindrical blank for the production of an
eccentric roller comprising a core and a rim may
be produced, the inner portion of said blank being
shaped to substantially the form of the core of
said roller, the outer portion of said blank being
50 shaped to substantially the form of the rim of said
roller, and a web connecting said inner and outer
portions of said blank.

2. A cylindrical forging for the production of
an eccentric roller having a core and a rim, said
55

- forging comprising an inner and an outer portion, a connecting web separating said portions, said inner portion being forged substantially to the form of the core of said roller and said outer portion being forged substantially to the form of the rim of said roller.
3. The method of producing an eccentric roller having a core and a separate rim comprising die forging a unitary blank to shape the inner portion of said blank to the form of said core and the outer portion of said blank to the form of said rim and provide a connecting web between said inner and outer portions, forming an opening in said core offset from the center thereof, removing said core and rim from said blank, machining the outer circumference of said core and the inner circumference of said rim and interposing an anti-friction bearing between said core and said rim.
- 20 4. A blank for the production of a roller having a core and a separate rim, said blank comprising inner and outer portions, said inner portion being shaped substantially to the form of the core of said roller and embodying a peripheral member and a relatively thinner web, the outer portion including inner and outer peripheral members and an intermediate member of reduced thickness and a web connecting said inner and outer portions of said blank.
- 25 5. A blank for the production of an eccentric roller having a core and a separate rim, said blank comprising inner and outer portions, said inner portion being shaped substantially to the form of the core of said roller and embodying a peripheral member and a relatively thinner web, said peripheral member having a section of reduced thickness, the outer portion including inner and outer peripheral members and an intermediate member of reduced thickness, and a web connecting said inner and outer portions of said blank.
- 30 6. The method of producing a roller having separate core and rim members comprising subjecting a blank to a die forging operation to form simultaneously the shaped core member and shaped rim member of said roller, separating said core and rim members, machining the outer circumference of said core member, machining the inner circumference of said rim member and interposing an anti-friction bearing between said core and rim members.
- 35 7. The method of producing a roller having separate core and rim members comprising subjecting a blank to a die forging operation to form simultaneously the shaped core member and shaped rim member of said roller and a relatively thin web connecting said members, removing said web, machining the outer circumference of said core member, machining the inner circumference of said rim member and interposing an anti-friction bearing between said core and rim members.
- 40 8. The method of producing a roller having separate core and rim members comprising subjecting a blank to a die forging operation to form simultaneously the shaped core member and shaped rim member of said roller and a relatively thin web connecting the outer circumference of said core member with the inner circumference of said rim member, simultaneously removing said connecting web and machining said circumferences of said core and rim members and interposing an antifriction bearing between said core and rim members.
- 45 9. The method of producing a roller having separate core and rim members comprising simultaneously shaping said core and rim members by a forging operation in a single forging die, separating said core and rim members, machining the outer circumference of said core member, machining the inner circumference of said rim member and assembling said members into said roller.
- 50 10. A blank for the production of a roller having separate core and rim members, said blank comprising a unitary structure having an inner portion embodying a web and relatively thicker oppositely extending circular flanges projecting from said web and forming the core member of said roller, and an outer portion including spaced oppositely extending circular flanges and an intermediate relatively thinner web and forming the rim of said roller, said inner and outer portions being formed into said unitary structure by a relatively thin connecting web, said flanges of said inner portion being of increased width below the center of the web of said inner portion and including a section of reduced thickness.

WILFRED A. BEAUCHAMP.
